DESIGN FOR A BUTTON CLEANER SHIELD

Samuel Lapin, New York, N. Y., assignor to Publix Metal Goods Corp., New York, N. Y., a corporation of New York

Application August 26, 1941, Serial No. 103,019

Term of patent 7 years

To all whom it may concern:

Be it known that I, Samuel Lapin, a citizen of the United States of America, residing in the Borough of Manhattan, city of New York, county of New York, and State of New York, have invented a new, original, and ornamental Design for a Button Cleaner Shield, of which the following is a specification, reference being had to the accompanying drawing, forming a part thereof.

Figure 1 is a front elevational view of a button cleaner shield showing my new design.

Figure 2 is an end elevational view as seen from the left end of Figure 1.

Figure 3 is a front elevational view of Figure 1 with the parts in extended position.

Figure 4 is a rear elevational view of Figure 3.

Figure 5 is an edge view of Figure 4.

Figure 6 is a longitudinal horizontal sectional view as seen from the plane 6—6 on Figure 5.

I claim:

The ornamental design for a button cleaner shield, substantially as shown.

SAMUEL LAPIN.
